GAME BOARD

Jack Seidman, Philadelphia, Pa., assignor to Spot-O-Gold Corporation, Philadelphia, Pa.

Filed Apr. 16, 1970, Ser. No. 22,614

Term of patent 14 years

Int. Cl. D21—01

U.S. Cl. D34—5

FIG. 1 is a perspective view of a game board showing minute design;

FIG. 2 is a rear elevational view thereof;

FIG. 3 is a side elevational view showing a side not illustrated in FIG. 1; and

FIG. 4 is a bottom plan view.

The rows of discs are an integral part of the game board.

I claim:

The ornamental design for a game board, substantially as shown and described.
